UNITED STATES PATENT OFFICE.

HARRY N. FARIS, OF KANSAS CITY, KANSAS.

TELEPHONE RINGING DEVICE.

1,007,684.

Specification of Letters Patent. Patented Nov. 7, 1911.

Application filed February 13, 1909. Serial No. 477,762.

To all whom it may concern:

Be it known that I, HARRY N. FARIS, a citizen of the United States of America, and a resident of Kansas City, county of Wyandotte, and State of Kansas, have invented a new and useful Improvement in Telephone Ringing Devices, of which the following is a specification.

My invention pertains to methods and apparatus for generating ringing currents in a telephone central office for the purpose of ringing telephone bells.

My object is to provide a system of current generating devices which will operate effectively in delivering ringing currents when called upon to do so, and will maintain a condition of readiness for operation during those periods when not called upon for delivery of ringing current, the condition of readiness for action being maintained at a minimum of wasted energy.

My invention is designed primarily for use in connection with current generating systems in which the prime source of energy is a galvanic battery associated with an inductive transformer, and the method which I use to conserve the energy of the battery when the system is not called upon to deliver ringing current is to open the battery circuit supplying the primary winding of the transformer during the periods when current is not required, and to close the circuit automatically when the ringing current is required. The means which I use to accomplish this result is embodied in a portion of the current generating equipment, and as a result of such embodiment the current generating equipment acts automatically and as a complete unit delivering a current suitable for ringing whenever a circuit is provided through which said current may be delivered and acting to maintain itself in a state of readiness to deliver such current at all times, but with a minimum consumption of energy when a circuit for the delivery of current does not exist.

In the drawings accompanying, Figure 1 shows a preferred form and Fig. 2 a modified form of the circuit of my invention. Fig. 3 shows essential portions of the circuit of a telephone switchboard.

The divers units of apparatus involved are not necessarily especially designed for use in my invention and for that reason specific mechanical details are not given, all

parts being represented by recognized symbols.

Referring first to Fig. 1, J and M are conductors leading to the ringing bus bars of the telephone switchboard. Conductor J passes through winding of relay R with shunt lamp L¹ to terminal H of secondary S of the transformer. The conductor M may pass through contact E and armature A of relay R to the terminal N of the secondary S of the transformer when the relay R is energized, and at other times it is connected through battery B¹ and resistance lamp L² to the terminal N. It will be seen that when an external circuit is provided from J to M that current from B¹ will flow, energizing relay R and closing the path from M to N directly.

Battery B² supplies energy continuously for operating the vibrator armature V by control of its back contact Y and magnet Q. Magnet Q is shunted by the noninductive resistance F. The armature V vibrates continuously. By the vibrating armature V and its contacts W and X the potential of battery B¹ passes out through keys K¹ and K² and primary windings P¹ and P² to junction point I, thence to N, thence to armature A of relay R, where the circuit is open; hence current does not flow. Upon the closure of an external path between conductors J and M, current flows through M, B¹, L², N, S, H, R, J and external path energizing R and closing A to E. The closure of A to E removes the potential of battery B¹ from N, S, H, R and external path (leaving the lamp L² as a direct resistance across battery B¹) and therefore depriving R of the current which energized it. By the closure of A to E, however, current is permitted to flow through B¹, V, W, K¹, P¹, I, N, A, E, (and alternatively through X K² P²), thus energizing the transformer, and creating an alternating potential in the secondary S which then furnishes a ringing current through the circuit, M, E, A, N, S, H, R, J, and the external path. The relay R is thus provided with alternating current immediately upon the cessation of the direct current causing its initial energization and the intensity of this current will be equal to or greater than a predetermined minimum value since the external path from J to N must be below a predetermined maximum resistance to cause the energizing of relay R primarily. The 110

relay R is one adapted to retain its armature in attracted position when energized by alternating or pulsatory ringing current. Relays of this type are obtainable commercially. Usually they have a very heavy armature A which is so sluggish in beginning its return movement that it is reattracted by an energization of the core before its return has been effected.

10 It will be seen that during periods of idleness no current from battery B¹ is used and that a normal current from battery B² is used. The potential of battery B¹ is upon the conductors J and M which are open at 15 the telephone switchboard. Upon the closure of conductors J and M through the external path the potential of battery B¹ is removed from those conductors and the path from those conductors through the generating device is cleared of all apparatus other than 20 the potential generating winding S and controlling relay R. The conditions thus are suitable for generating a maximum current for ringing purposes, being those encountered in a continuously operating transformer with the addition of the controlling relay R.

10 In ringing upon metallic circuit telephone lines, the external path from J to N will be 30 found through the line's conductors and the ringer bridge of the telephone sub-station. This will give a maximum resistance of probably 1500 ohms. In ringing upon grounded telephone lines the ringing bridge 35 at the substation will include a ground connection and this ground connection may be defective from any one of several causes: The connection may be of high resistance by reason of defective contact between conductors; the connection may be to earth by 40 means of a ground rod driven in dry earth, which is likely to be of abnormally high resistance for ringing purposes; the earth connection may be polarized; the earth current from street railway or other sources may 45 oppose the potential of battery B¹ and effect a reduction of current. To obviate interference in my automatic ringing device through any of these causes, by rendering 50 it independent of the ground connection, or indeed, of any connection at the telephone sub-station, I provide a circuit wholly within the central office, which circuit may be completed by the operation of connecting 55 the ringing bus bars of the switchboard to the conductors of the line to be rung upon.

10 In the circuit of lines of some well known types of telephone switchboards the jack body J¹ is connected to earth through the 60 winding of cut-off relay R¹. In such a switchboard when the plug P³ is inserted in the jack and ringing key K³ is operated the conductor M is connected through conductor T plug P³ jack J¹ and relay R¹ to 65 earth. Through conductor J a path is taken

through impedance O to earth at G. Thus I establish a local path from M through K³, T, P³, J¹, R¹, earth, G, O to J, within the central office of the telephone exchange, which local circuit contains only the usual elements of the telephone equipment, and the elements contained in my ringing current generating device. This circuit is adapted to be closed by the act of ringing upon any telephone line whether metallic or 70 grounded. By this circuit the relay R is provided with a circuit of maximum resistance which is entirely independent of the resistance, or of the operativeness or inoperativeness of the line attempted to be 75 rung upon, and my improved ringing device will deliver the desired ringing potential to that line. At the same time the local circuit thus secured will maintain the energization of relay R by alternating current 80 from winding S without the coöperation of the line attempted to be rung upon.

10 In Fig. 2 a modification is shown in which relay R has a back contact D adapted to remove potential of battery B¹ from the circuit of conductors J and M. It is obvious that relay R may be constructed in any of a large number of permutations with respect to its armature contacts. Keys K¹ and K² are introduced for the purpose of ringing 95 biased polarized telephone bells selectively. It is known that the potential in the secondary winding caused by the breaking of the primary circuit is much greater than the potential caused by the making of the primary 100 circuit, and the design of the transformer having the secondary S and split primary P¹ and P² is such that the potential of the breaking of the primary circuit is obtained in the secondary winding first in one direction and then in the opposite direction. By 105 this means a uniform alternating current is secured, the currents in a positive direction being equal to the currents in the negative direction and alternating with them. By 110 opening key K¹ preparatory to ringing upon a telephone line, primary winding P¹ will not be permitted to carry current, and currents generated in secondary S will be solely 115 those resulting from current through primary P². The result will be a distorted alternating current in which the potential of the waves of one polarity will be much in excess of the potential of the waves of the other polarity. Such current is suited for 120 ringing biased polarized bells. The polarity of biased or pulsatory current may be predetermined by operating keys K¹ or K² as desired. By including in the conductor J or conductor M a source of direct current, 125 the objectionable phase of the distorted current thus produced may be opposed and eliminated, the desired phase being, at the same time, amplified, and the current thus becoming all that is required for ringing biased 130

5 bells. It will be noted also that the periodicity of the resulting current is proper for such bells. I have shown two batteries, B¹ and B². The battery B¹ is inactive except during the operation of ringing, and the battery B² is active at all times to maintain the vibration of the armature V. It is desirable that the armature V operate continuously to secure clearly cut signals in ringing 10 codes. Where ringing codes is not required it is obvious that the energy of the battery B² may be conserved by including in its circuit a contact controlled by armature A of the relay R. By maintaining battery B² 15 separate from battery B¹, battery B¹ is ready to give its full current in the primary circuit of transformer, even though battery B² may be to some extent deteriorated by its continuous service in operating the vibrator. 20 It may be found a convenience in many instances also to have these batteries of different potentials. It is obvious that the two circuits may be operated upon the same battery where this is desirable, as is the case 25 where a storage battery forms a part of the central office equipment, and my invention is not in any way limited to a system in which two batteries are included. I have illustrated this by showing the switch Z 30 adapted to connect together batteries B¹ and B² in Fig. 1, thereby uniting them into a single battery.

It is obvious that many modifications may be made without departing from the scope 35 of my invention.

What I claim as new and desire to secure by United States patent is:

1. In a telephone ringing system, a transformer containing secondary and primary 40 windings; a secondary circuit containing said secondary winding, and adapted to be closed through an external path; a relay also included in said secondary circuit; and a primary circuit including said primary 45 winding, a source of current and contacts of said relay.

2. In a telephone ringing system, a transformer containing secondary and primary windings; a secondary circuit containing 50 said secondary winding, and adapted to be closed through an external path; a relay also included in said secondary circuit; and a primary circuit including said primary winding, a source of current and normally 55 open contacts of said relay.

3. In a telephone ringing system, a transformer containing secondary and primary windings; a secondary circuit containing 60 said secondary winding, and adapted to be closed through an external path; a source of constant potential and a relay also included in said secondary circuit; and a primary circuit including said primary winding, a source of current and contacts of said 65 relay.

4. In a telephone ringing system, a transformer having primary and secondary windings; a secondary circuit including a source of current, a relay and said secondary winding, said relay being adapted to remove by the operation of its armature any direct current which may have been flowing in said secondary circuit, from said source of potential, prior to the operation of said relay. 70

5. In a telephone ringing system, a transformer having a primary and a secondary winding; a secondary circuit including a source of current, a relay and said secondary winding; said relay being adapted to shunt by the operation of its armature any direct current (from said source of potential) 75 which may have been flowing in said secondary circuit prior to the operation of said relay. 80

6. In a ringing system for telephone exchanges, a transformer having primary and secondary windings; a secondary circuit including in the order named: a relay, a secondary winding, a resistance and a battery and means for connecting a path to complete 85 the circuit, a contact of said relay being adapted to close a shunt about said battery and said resistance. 90

7. In a telephone ringing system, a transformer containing secondary and primary 95 windings; a secondary circuit containing said secondary winding and adapted to be closed through an external path; a primary circuit including said primary winding; a source of current and vibrator contacts; and a relay whose winding is included in said secondary circuit and which is adapted to render said primary circuit operative. 100

8. In a telephone ringing system, a transformer containing secondary and primary 105 windings; a secondary circuit containing said secondary winding and adapted to be closed through an external path; a primary circuit including said primary winding, a source of current and vibrator contacts; and means controlled by said secondary circuit and controlling said primary circuit to render said primary winding active or inactive. 110

9. In a telephone ringing system, a transformer having primary and secondary windings; a secondary circuit including a source of current, a relay and said secondary winding, said relay being adapted to remove by the operation of its armature any direct current which may have been flowing in said 120 secondary circuit from said source of potential prior to the operation of said relay, and to render said primary winding active. 115

10. In a telephone ringing system, a transformer having a primary and a secondary 125 winding; a secondary circuit including a source of current, a relay and said secondary winding; said relay being adapted to shunt by the operation of its armature any direct current which may have been flowing 130

in said secondary circuit prior to the operation of said relay, and to render said primary winding operative.

11. In a ringing system for telephone exchange, a transformer having primary and secondary windings; a secondary circuit including the following elements and connected in series in the order named: a relay, a secondary winding, a resistance and a battery and means for connecting a path to complete the circuit, a contact of said relay being adapted to close a shunt about said battery and said resistance; and a primary circuit path connected in multiple with said resistance and containing vibrator contacts and a primary winding of said transformer.

12. In a ringing system, a device constituting a source of ringing current adapted to be rendered operative by the closing of a conducting path between its terminals; a branch conductor from one terminal of said device to a common-return conductor; a connection in the telephone switchboard from said common-return to a line conductor of a telephone line; and a ringing key constituting means for connecting said line conductor to the remaining terminal of said source of ringing current.

13. In a telephone ringing system, a transformer containing secondary and primary windings; a secondary circuit containing said secondary winding and adapted to be closed through an external path; a relay also included in said secondary circuit; a primary circuit including said primary winding, a source of current and contacts of said relay;

a ground branch connection upon one terminal of said secondary circuit; and external path including a ringing key, a talking conductor and a cutoff relay winding.

14. In a telephone ringing system, a transformer containing a secondary and two primary windings; a secondary circuit containing said secondary winding and adapted to be closed through an external path; a relay also included in said secondary circuit and a primary circuit including a source of current, normally open contacts of said relay, and a vibrator closing circuit through said primaries alternately; and other means for interrupting the conductor of one only of said primaries.

15. In a telephone ringing system, a transformer containing a secondary and two primary windings; a secondary circuit containing said secondary winding and adapted to be closed through an external path; a relay also included in said secondary circuit; and a primary circuit including a source of current, normally open contacts of said relay, and a vibrator closing circuit through said primaries alternately; and other means permitting the closure of but one of said primaries.

Signed by me at Kansas City, county of Jackson and State of Missouri, in the presence of two witnesses.

HARRY N. FARIS.
